UNITED STATES PATENT OFFICE.

WALTER F. STIMPSON, OF DETROIT, MICHIGAN, ASSIGNOR TO ESTELLE H. STIMPSON,
OF DETROIT, MICHIGAN.

DESIGN FOR A SCALE-FRAME.

52,901.

Specification for Design.

Patented Jan. 14, 1919.

Application filed August 26, 1916. Serial No. 117,116. Term of patent 14 years.

To all whom it may concern:

Be it known that I, WALTER F. STIMPSON, a citizen of the United States of America, residing at Detroit, in the county of Wayne and State of Michigan, have invented a certain new, original, and ornamental Design for Scale-Frames, of which the following is a specification, reference being had therein

to the accompanying drawings, in which the figure is a perspective view showing a scale having a base A, an upright B and an indicating portion C.

I claim:

The ornamental design for a scale frame substantially as shown.

WALTER F. STIMPSON.
